B. B. GAFFIN

BUBBLE PIPE

Filed Oct. 23, 1926

Fig. 3.

Inventor

Benjamin Bernard Gaffin

By his Attorney

Daniel L. Morris

UNITED STATES PATENT OFFICE.

BENJAMIN BERNARD GAFFIN, OF BROOKLYN, NEW YORK.

BUBBLE PIPE.

Application filed October 23, 1926. Serial No. 143,561.

The present invention relates to improvements in devices for use particularly in the formation of soap bubbles, although the invention is not confined to such use but may 5 be employed for many similar purposes and will find utility in other arts, such as glass blowing.

The object of the invention is to provide a device of this class which is in the form of 10 a pipe and provided with means for increasing the adhesion between the bubble and the end of the pipe whereby the formation of bubbles of the size desired is facilitated.

With this end in view, the extremity of 15 the pipe is constructed with a number of longitudinally extending slits arranged around the circumference thereof and the frayed ends thus formed are bent outwardly at angles to the axis of the pipe, thus providing a large surface to which the bubble 20 may adhere and a construction which is simple, cheap and effective in service.

For a more complete understanding of the invention, reference will now be had to the 25 accompanying drawings forming a part of this specification, which disclose the preferred form of the invention, and in which

Figure 1 is a longitudinal view of the device; showing the manner of forming a 30 bubble;

Figure 2 is a similar view without the bubble;

Figure 3 is an end view, showing the 35 nature of the frayed ends.

Referring now to the drawings, the device disclosed embodies a long slender pipe, 10, of aluminum or similar material by means of which the bubbles are adapted to be blown in a well-known manner. The extremity of 40 the pipe on which the bubbles are formed is frayed to form prongs, 11, extending at

acute angles to the axis of the pipe. These prongs are preferably formed by slitting the extremity of the pipe longitudinally (as by means of snips or the like) at a plurality 45 of points around its circumference and the frayed ends are then bent outwardly. The prongs so formed provide a large adhesive surface for the bubbles, thus resulting in a construction whereby bubbles of the desired 50 size may be easily blown.

It will be noted that the above construction is very simple and the device so made can be manufactured and sold cheaply. Although of great simplicity and low cost, it is 55 withal very effective when used for the purpose designated. The divergence of the prongs may be adjusted simply by bending them and thus the optimum divergence of said prongs may be determined. This will 60 perhaps vary to some extent depending on the size of bubble desired, although the angles of the prongs with the axis of the pipe should never reach or exceed ninety degrees and for the most part angles of about 65 forty-five degrees will be found satisfactory.

Although I have described a specific embodiment of the invention, I do not desire to be limited thereto as various slight changes and modifications may be made therein within the spirit and scope of the invention and of the appended claim.

I claim:

A device for blowing bubbles comprising a pipe having at one extremity a plurality 75 of longitudinal slits disposed circumferentially and forming frayed ends, said frayed ends being bent outwardly into prongs.

In testimony whereof, I have signed my name to this specification this 19th day of October, 1926.

BENJAMIN BERNARD GAFFIN.
